L. MUTHER

FOLDING MACHINE

Filed Dec. 1, 1922

Fig. 1.

UNITED STATES PATENT OFFICE.

LORENZ MÜTHER, OF NEWTON, MASSACHUSETTS.

FOLDING MACHINE.

Application filed December 1, 1922. Serial No. 604,870.

To all whom it may concern:

Be it known that I, LORENZ MÜTHER, a citizen of the United States, residing at Newton, in the county of Middlesex and State of Massachusetts, have invented a new and useful Improvement in Folding Machines, of which the following is a specification, reference being had therein to the accompanying drawings.

10 This invention relates to folding machines but is more especially designed with reference to machines for folding a binding tape around the edge of sheet material.

In the manufacture of shoes, it has been 15 customary to provide certain styles with what is known as "cord" binding. This is accomplished by stitching a piece of tape or suitable fabric to the right side of the shoe part or material to be bound at its edge, 20 then by turning the binding in a reverse direction over the stitching concealing it and around the edge of the material and by pressing the free edge of the binding material down upon the reverse side of the shoe 25 part or other material; the engaging surfaces having previously been treated with cement. When the binding is turned tightly and smoothly around the edge of the material to be bound, a finished and attractive 30 cord edge is presented. It is essential, however, in this work that the binding material be turned tightly and smoothly about the edge of the bound material, otherwise the binding becomes loose and wrinkled when 35 subjected to wear and destroys the attractive appearance of the shoes.

The main object of this invention is the provision of a machine adapted for this work which contains the minimum number 40 of operating instrumentalities, and which is of simple construction and operation and yet efficient.

Another object of the invention is the provision of means for giving the binding a 45 preliminary upward turn around the edge of the material as it is guided through the machine thereby preparing the binding for the folding means to avoid straining its edge.

50 Further objects of the invention will be more specifically set forth and described hereinafter.

The main feature of my invention resides 55 in the provision of means adapted both to guide the material as it is fed through the machine and to give the binding a prelimi-

nary upward turning to prepare it for the folding means. In work of this character it is essential to good results that the binding be turned around the edge of the material without being subjected to strain, otherwise the pressed down portion of the binding is liable to be loosened by the strain as the work is fed forward. This is especially true when the operative parts of the machine 60 are closely grouped which is a desirable condition for the best work. Preferably, I accomplish this preliminary turning by providing a fixed member, provided with a guiding face, substantially perpendicular to 65 the work-support and slightly curved away from the normal line of feed, so that, as the material is fed forward the curved face turns the binding upwardly around the edge of the material into a vertical position ready 70 to be turned downwardly by the folding member. Since the guiding is accomplished by contact with the outer surface of the binding there is nothing to interfere with the binding as it is turned around the edge 75 of the material and the binding is free at all times to assume natural lines of curvature without strain.

In the drawings illustrating the preferred embodiment of my invention, Figure 1 is an 80 end elevation of a portion of a folding machine having my invention applied thereto; Fig. 2 is a side elevation of the same as viewed from the operator's seat; Fig. 3 is a view in perspective of the folding member; Fig. 4 is a view in perspective of one form 85 of means for guiding and imparting a preliminary turning of the binding; and Fig. 5 is a plan view of a portion of the work-support and the folding instrumentalities 90 showing their relative arrangement.

In the drawings my invention is shown as applied to a folding machine of the general type illustrated and described in United States Letters Patent No. 1,294,919, issued 95 to William F. Lautenschlagé on February 18, 1919. The operative end only of the machine is shown since the actuating mechanisms for giving such folding instrumentalities, as are retained, their appropriate movements are the same as shown in said patent 100 and operate in the same manner.

Referring to the drawings, 15 indicates 105 the end of the lower arm, and 16 the end of the upper arm of the frame of the machine, 19 the lift-shaft, 20 the feed-bar and 21 an idler roll. The feed-bar is mounted

in a housing 22, carried by a clamp-bearing 23 and the forward and backward movement is imparted to the feed-foot 24 by the rocking of the housing 22. An arm 25, fixed 5 on the end of the lift-shaft 19, is connected by a link 26 to a stud 27 carried by a split collar 28 secured to the upper end of the feed-bar 20, and the rocking of the lift-shaft 19 through these means imparts an up 10 and down movement to the feed-bar 20 in the housing 22. The feed-bar is held in a lowermost position by a spring 30, and the idler roll with which the feed-foot co-operates in the feeding movement is loosely 15 mounted upon a screw stud 32 set in the end of the lower arm.

Through the foregoing, the feed-foot is given a four-motion feed. In its forward movement (away from the operator) it is in 20 a lowermost position, co-operating with the idler roll to feed the material forward in the machine. At the end of the feeding movement, the rocking of the lift-shaft 19, through the medium of the arm 25, link 26 25 and collar 28, lifts the feed-bar 20 and feed-foot 24 to release the material and holds them in a raised position during their movement backward at the end of which they are dropped into initial position. The material is therefore fed in a step-by-step manner. All of the foregoing construction and mode of operation is fully shown and described in said Lautenschlager patent to which reference may be had.

35 For turning the binding over downwardly toward the reverse side of the material, a folding member 50 may be mounted upon a work-support 51 on the lower arm 15. The folding member 50 is in the form of a plow 40 having an oblique face 52 adapted to be engaged by the binding as the material is fed forward, the forward edge 54 of the folding member being in the form of a concave curve to turn the binding downwardly over the 45 reverse side of the material as it passes under the nose 55 of the folding member. This member is provided with a slot 56 adapted to receive a screw 57 whereby it may be adjustably secured to the work-support 51. The folding member in general form is 50 similar to the plow of the Lautenschlager machine, but its oblique surface and curved edge are modified to suit the particular work required in applying cord binding.

55 For pressing down the turned-over tape upon the reverse side of the material to be bound, a presser-arm 60 carrying a presser 62 substantially L-shaped in plan is either made integral with or fixedly mounted on a lever 65, secured thereto by a screw 66 and held against rotation thereon by a pin 67. The lever 65 is provided with a shaft 68 mounted in the bearing 70 formed on the upper arm 16 and is arranged to oscillate 60 therein.

Secured in the perpendicular portion of the lever 65 is a threaded screw 72 having a check nut 73, and adapted to engage at its end a block 76, set in an arm 77, fixedly mounted on the end of the lift-shaft 19. 70 Through the medium of these parts, the lever 65 is rocked by the oscillation of the lift-shaft 19 to raise and lower the presser arm and presser member, and the machine is so timed that the presser member is down between the feeding movements and elevated during the feeding movements. To hold the lever 65 in the position shown in Fig. 1, with the end of screw 72 abutting the block 76, a spring 80 set in a hollow screw 81 80 bears against the upper portion of the lever 65. The screw is threaded through an arm 83 forming a part of the upper arm 16 of the machine, and the pressure exerted upon the lever 65 by the spring 80 may be adjusted by turning the screw one way or the other.

The particular construction hereinbefore except the modification in form of the folding member constitutes no part of the present invention. The particular form of pressing member is shown and described in an application for Letters Patent filed by me jointly with Frederick S. Glines in the United States Patent Office on July 24, 95 1922, Serial Number 576,965, to which reference may be made for a more detailed description of the same.

The novel features of the present invention reside in the provision of fixed guiding means for giving a preliminary turning to the binding. This member may be made in various forms, but preferably is constructed as shown in Fig. 4 of the drawings, comprising a flat plate 85 provided with a slot 86 to receive a screw 87, whereby it may be secured to the work-support 51, the slot permitting of a limited longitudinal adjustment. On its forward end, the plate is turned upwardly forming a gauge 88 having a guiding and turning face 89, which is substantially perpendicular to the plane of the plate 85. This face is slightly curved in a direction away from the normal line of feed on its forward portion or the portion nearest the operator.

The operation of the machine is as follows: The material is presented to the machine with the right side downward and with the binding turned over the stitching in a reverse direction and extending outwardly from the material and is inserted between the feed-foot and the idler roll, the feed-foot being in its initial position ready for feeding. In this initial position the work is held tightly against the gauge 88, the binding at that point being turned upwardly around the edge of the material to be bound, and in engagement with the gauge. The machine is then started. As the feeding 120 125 130

mechanism feeds the material one step, the curved portion of the face 89 turns the binding upwardly into a position perpendicular to the work support in which position the 5 binding is presented to the curved face 52 of the folding member where it is turned downwardly to slide under the edge 54 ready for the pressing operation. During this movement the material is held pressed 10 against the face 89 of the gauge 88 and thereby guided through the machine. After the feeding is completed the pressing member descends and presses the turned over binding down upon the reverse side of the 15 material in a cemented relation thereto. The work is thus fed through the machine in a step-by-step manner.

It will be observed that since the gauge guides the material by contact with the 20 outer face of the binding rather than by engagement with the edge of the material itself, the binding is free to be turned naturally by the curved face of the gauge, and to be delivered in that condition to the 25 folding member. This permits the gauge and folding member to be closely grouped with the other folding instrumentalities which is so requisite to perfect work.

It is further to be noted that my invention 30 both simplifies the construction and number of operative parts and performs all the necessary functions required in the folding operation.

It is to be understood that my invention 35 is not to be limited to the exact form or the exact application herein shown and described, since it may be embodied in other forms of construction and may be applied to other forms of folding machines all within 40 the purview of the following claims:

What I claim is:

1. In a folding machine, the combination 45 of means for feeding material having a binding attached to one edge thereof, of a fixed member having its operative face perpendicular to the body of the material for turning said binding around the edge of said material and into an upright position, a plow for turning said upright binding downwardly toward the body of said material and means for pressing said binding upon the body of said material; said fixed member and said plow being so positioned in relation to each other that said 50 upright binding is delivered by the feeding means from said fixed member to said plow in position to be turned down by the latter without straining the edge thereof.

2. In a folding machine, the combination

with means for feeding material having a 60 binding attached to one edge thereof, of a work-support, a member having a guiding face perpendicular to said work-support and approximately parallel to the normal line of feed for turning said binding upwardly around the edge of said material, a plow for turning said upright binding down toward the reverse side of said material, said plow being arranged in close 65 proximity to said member and positioned to receive said binding from said member and to turn it downwardly in a natural curve without straining the edge thereof, and means for pressing said binding down upon the reverse side of the body of said 70 material.

3. In a folding machine, the combination 75 of means for feeding material having a binding attached to one edge thereof, of a work-support, a member having a guiding face perpendicular to said work-support and curving slightly in a forward direction toward the normal line of feed for turning the said binding up around the edge of said material into an upright position, said member being adjustable transversely on said work-support, a plow in close proximity to said guiding member and in position to receive said upright binding 80 from said member and to turn it downwardly toward the body portion of said material without straining the edge thereof and means for pressing said binding down upon the reverse side of the body of said material.

4. In a folding machine, the combination 85 of means for feeding material having a binding attached to one edge thereof, of a work-support, a member having a guiding face perpendicular to said work-support and curving slightly in a forward direction toward the normal line of feed for turning the said binding closely around the edge of said material into an upright position, a plow forward of and in close 90 proximity to said guiding member, the nose 95 of said plow projecting transversely beyond said guiding member toward the normal feeding line, said plow being in position to receive said upright binding from said guiding member and to turn it downwardly 100 toward the body portion of said material without straining the edge thereof and a hammer for pressing said binding down upon the body of said material.

In witness whereof, I hereunto set my 110 hand this 25th day of November, 1922.

LORENZ MUTHER.
